UNITED STATES PATENT OFFICE.

ERNEST E. KOKEN, DECEASED, LATE OF ST. LOUIS, MISSOURI; WALTER F. KOKEN, EXECUTOR.

TWO-WAY FAUCET.

960,558.

Specification of Letters Patent. Patented June 7, 1910.

Application filed January 24, 1910. Serial No. 539,761.

To all whom it may concern:

Be it known that ERNEST E. KOKEN, deceased, late a citizen of the United States, and resident of the city of St. Louis and State of Missouri, did invent a certain new and useful Improvement in Two-Way Faucets, of which the following is a specification.

This invention relates to two-way faucets.

It has for its principal objects to produce a two-way faucet which is simple in construction and can be readily manipulated; to provide for the discharge of either cold or hot water or a mixture of cold and hot water through one or the other of the discharge nozzles; to regulate the mixture; to regulate the flow; and to attain certain other advantages hereinafter more fully appearing.

The invention consists in the parts and in the arrangements and combinations of parts hereinafter described and claimed.

In the accompanying drawings which form part of this specification, and wherein like symbols refer to like parts wherever they occur, Figure 1 is a fragmentary view of a two-way faucet embodying the invention, the valve mechanism being shown in vertical longitudinal section; Fig. 2 is a transverse section on the line 2-2 of Fig. 1. Fig. 3 is a transverse section on the line 3-3 of Fig. 1; and, Figs. 4 and 5 are detail views of the cylindrical rotatory valve-blocks.

As shown in the drawings, the device comprises a valve-casing 1. Extending laterally from the valve-casing is a discharge nozzle 2 which is usually arranged to discharge into a lavatory or basin in a well known manner. Extending upwardly from the valve-casing is an elongated nozzle or pipe 3 whose upper end portion is curved or bent so as to discharge downwardly as at 4. In the upper portion of the valve-casing 1 is a passageway 5 which communicates with the discharge nozzle 3 while in the side portion of said casing is a second passageway 6 which communicates with the discharge nozzle 2. The valve-casing 1 is bored cylindrically from its opposite ends and it is provided with a transverse partition 7. The partition is located substantially midway between the ends of the valve-casing and it is provided with a central opening or bore 8. In the cylindrical chamber on one side of the par-

ition 7 is rotatably fitted a cylindrical valve-member 9 which is hollowed out or chambered as at 10 and provided with a head 11 at its outer end.

The valve-member 9 is provided in its annular portion with a port opening 12 which is adapted to register with a port opening 13 in the valve-casing which communicates with the passageway 5 leading to the upper nozzle member 3. The port opening in the valve-member 9 is also adapted to register with a port opening 14 in the valve-casing which communicates with the passageway 6 leading to the discharge nozzle 2. The port openings 13 and 14 are arranged, preferably, at an angle of ninety degrees with respect to each other, and the valve-member 9 is rotated a quarter turn to bring its port opening 12 from one to the other of said port openings 13 and 14.

In the chamber on the opposite side of the partition 7 are two port openings 15, 16. The opening 15 communicates with a passageway 17 which in turn communicates with a supply pipe 18. The opening 16 communicates with a passageway 19 leading to the supply pipe 20. For the purposes of illustration, the pipe 18 will be hereinafter referred to as the cold water pipe, and the pipe 20 as the hot water pipe. Rotatably mounted in the chamber in the valve-casing on the side of the partition 7 opposite that on which the valve-member 9 is located, is a second cylindrical valve-member 21 which is bored or chambered and has a head 22 at its outer end. The valve-member 21 is provided with port openings 23, 24, which are adapted to register with the port openings 15, 16, respectively, in the valve-casing. The port openings 15, 16 in the valve-casing lie in the same longitudinal plane; and the port openings 23, 24 in the valve-member 21 are so arranged with respect to each other that they alternately communicate with the port openings 15, 16. That is, the port openings 23, 24, which are each of substantially the same area as the respective port openings 15, 16, are so located that their adjacent longitudinal side edges are in the same plane. By this arrangement, the port opening 23 will not register with the port opening 15 when the port opening 24 registers fully with the port opening 16, and vice versa. However, the port opening 23 may be made to partially register with the port opening 119

15 when the port opening 24 partially registers with the port opening 16, and such partial registration of the port openings may be varied so that the area of the communicating opening between the chamber 25 in the valve-member 21 and one of the supply pipes may be larger than the communicating opening between said chamber 25 and the other of said supply pipes.

10 The valve-member 21 is provided with a second set of port openings 23^a, 24^a, which are located with respect to each other in a manner similar to the before-mentioned port openings 23, 24; but one set of openings is located at substantially an angle of ninety degrees with respect to the other set. These openings are also located with respect to the port opening 12 in the valve-member 9 so that the port openings 23^a, 24^a communicate with the port openings 15, 16 at the time said port opening 12 communicates with the port opening 13 which leads into the passageway 5; and the port openings 23, 24 communicate with said port openings 15, 16 when said port opening 12 communicates with the port opening 14 which leads to the passageway 6. All of the above mentioned port openings except the opening 12 are of equal area; and the opening 12 is substantially twice the area of any of the other openings. By this arrangement, the full area of the port openings 13, 14 is open to communication with the chamber 10 when either of the port openings 23, 23^a, 24, 24^a, registers either partially or fully with the respective port openings 15, 16.

15 The passageway 8 in the partition 7 is surrounded by an annular flange 26 which is beveled to provide a seat for a beveled valve-member 27. The valve 27 is mounted on a cylindrical rod 28 which is adapted to be both rotated and reciprocated in the valve-casing 1. A portion of the rod is flattened as at 29 and 30 so as to slidably fit 20 in a counterpart axial hole in the heads 11, 22, respectively, of the rotatory valve-members 9, 21. By this arrangement the rod 28 may be moved endwise, without affecting the position of the valve-members 9, 21, so 25 as to open and close the valve 27 and establish or cut off communication, as the case may be, between the two chambers 10 and 25. When it is desired to rotate the valve-members 9, 21 it is only necessary to rotate the 30 rod 28; and for convenience in manipulating the same, it is provided with a handle 31.

35 The handle 31 is pivotally attached to the outer end of the rod 28, as at 32; and it has a downward extension 33 which is pivotally connected with one end of a link 34 whose opposite end is pivotally attached to a depending lug or ear 35 on a rotatable member 36 which is mounted concentrically of said rod 28. The member 36 is sleeved rotatably on the reduced end portion of a

packing gland 37. To prevent endwise movement of said member 36 with respect to said packing gland 37, the member 36 is provided with a set screw 38 having a rounded end portion which is adapted to fit in an angular groove 39 in the reduced end portion of said gland. By this arrangement, the rod 28 and the member 36 are rotated together, but endwise movement of said rod 28 is permitted independently of said member 36.

40 The valve-members 9, 21 are held in place by heads 40, 41, respectively, which are secured to the ends of the casing 1. The head 40 is provided with a nipple 42 on which the packing gland 37 is sleeved. The head 41 is provided with a pocket 43 which is adapted to receive the end of the rod 28 when the same is moved longitudinally to open the valve 27.

45 The operation of the device is as follows: Assuming that it is desired to discharge a mixture of hot and cold water through the nozzle or pipe 3. The valve-member 9 is turned to the position shown in Figs. 1 and 3; that is, the port opening 12 is moved into position to register with the port opening 13 in the valve-casing, at which time the port openings 23^a, 24^a in the valve-member 21 overlap the port openings 15, 16 in the valve-casing to the extent of substantially one-half their areas. In this position of the valve-members, an equal volume of water is supplied to the chamber 25 from each of the supply pipes 18 and 20. In this position, 50 also, the handle 31 stands vertically with respect to the axis of the rod 28. The handle 31 is then pushed inwardly to open the valve 27 whereby communication is established between the chamber 25 and the chamber 10. 55 The mixture of hot and cold water will then pass out through the port openings 12, 13, passageway 5, and into the nozzle or pipe 3. If it is desired to vary the temperature of the water, the handle 31 may be turned a few degrees to either side and thereby vary the proportionate areas of the port openings between the chamber 25 and the pipes 18 and 20. For example, if it is desired to raise 60 the temperature of the water which is discharged from the nozzle 3, the handle 31 is turned so as to rotate the valve-member 21 in the direction so as to enlarge the opening of communication between the port opening 24^a and the port opening 16 which communicates with the passageway 19; and to decrease the size of the opening of communication between the port opening 23^a and the port opening 15 which communicates with the passageway 17. On the other hand, if it 65 is desired to lower the temperature of the discharged water, the handle is turned in the reverse direction. If it is desired to discharge hot water only, the handle 31 is turned so as to rotate the valve-member 21 70

until the port opening 24* registers fully with the port opening 16 in the valve-casing, and communication is entirely cut off between the port opening 23* and the port opening 15 in the valve-casing. On the other hand, if it is desired to discharge cold water only, the handle 31 is moved to a corresponding position in the reverse direction, so as to move the valve-member 21 to bring the port opening 23* into position to register fully with the port opening 15 and cut off communication between the port opening 24* and the port opening 16. The area of the port opening 12 in the valve-member 9 is sufficient to always open communication through port opening 13 to the full extent of the area of said port opening 13 which is equal to the area of the individual port openings 15, 16, when the same are individually opened to their fullest extent, or to the combined partial opening of said two port openings 15, 16. Therefore, the area of the outlet port opening is always equal to the area of the inlet port opening or openings. The flow of the water through the discharge nozzle or pipe is controlled by manipulating the valve 27 to increase or decrease, as the case may be, the size of the opening between the chamber 25 and the chamber 10. When it is desired to discharge the water through the lower or lateral nozzle 2, the valve-members 9, 21 are rotated so as to bring the port opening 12 into communication with the port opening 14 which communicates with the passageway 6 and also bring the port openings 23 and 24 into position to register either alternately with the respective port openings 15 and 16 to their fullest extent, or simultaneously into partial communication with both of said port openings 15 and 16. The handle 31 will be manipulated to regulate the temperature and flow of the discharged water in a manner similar to that in which it is manipulated for the upper nozzle 3, except that its angular movement will be above and below a horizontal plane with respect to the axis of the rod 28.

Obviously, the device admits of considerable modification without departing from the invention. Therefore, it is not to be limited to the specific construction and arrangement shown.

What is claimed is:

1. A two-way faucet comprising a valve-casing having two chambers therein and means for establishing communication between said chambers, two discharge nozzles leading from said valve-casing and communicating with one of said chambers therein, two supply pipes communicating with the other chamber in said valve-casing, and connected valves in said valve-casing arranged to alternately establish communication with the respective supply pipes and

simultaneously establish communication through either of the respective discharge nozzles, and said valves being also arranged to simultaneously establish communication proportionately through both of said supply pipes when communication is established through either of the discharge nozzles. 70

2. A two-way faucet comprising a valve-casing having two chambers therein and means for establishing communication between said chambers, a lateral discharge nozzle and an upwardly extending discharge nozzle which is arranged to discharge above said lateral discharge nozzle, said discharge nozzles communicating with one of said chambers through separate port openings, two supply pipes communicating with the other chamber through separate port openings, and a valve arranged to alternately open communication through the port openings which communicate with said discharge nozzles, and another valve connected to said first-mentioned valve and arranged to alternately open communication through the port openings which communicate with said supply pipes when communication is established through either of the port openings which communicate with the discharge nozzles. 80

3. A two-way faucet comprising a valve-casing having two chambers therein and a passage-way connecting said chambers, a valve for controlling said passage-way, two

discharge nozzles leading from said valve-casing and communicating with one of the chambers therein through separate port openings, a valve-member in said chamber adapted to alternately open communication through said port openings which communicate with the respective discharge nozzles, two supply pipes communicating with the second chamber in the valve-casing through separate port openings therein, a valve-member in said second chamber adapted to alternately open communication through the respective port openings which communicate with the supply pipes, said valve-member being also adapted to simultaneously open communication proportionately through both of said port openings which communicate with the supply pipes, said valve-member in said second-mentioned chamber being so arranged with respect to the valve-member in the first-mentioned chamber that communication is established through the port openings which communicate with the supply pipes when the valve-member in the first-mentioned chamber establishes communication through either of the port open- 130

ings which communicate with the respective discharge nozzles, and means for simultaneously actuating the valve-chambers in said chambers and also for manipulating the valve which controls the passage-way between said chambers.

4. A two-way faucet comprising a valve-casing having two chambers therein which are connected by a passage-way, a valve for controlling said passage-way, two discharge nozzles leading from said casing and communicating with one of said chambers through separate port openings therein, a chambered valve-member in said chamber in the valve-casing, said chambered valve-member having a port opening arranged to alternately register with either of said port openings in the valve-casing, the other chamber in said valve-casing having two port openings which communicate with two separate supply pipes, a chambered valve-member in said second mentioned chamber in the valve-casing, said second mentioned chambered valve-member having a pair of port openings therein, one of said pair of port openings being arranged to register with one of the port openings in the valve-casing which communicates with one of the supply pipes and the other of said pair of port openings being arranged to register with the port opening in the valve-casing which communicates with the other supply pipe, and said pair of port openings in the valve-member being arranged to register simultaneously with both of said port openings in the valve-casing, said pair of port openings in the valve-member being also arranged so that when one of them registers fully with its coöperating port opening in the valve-casing the other one of said pair will not register with its coöperating port opening in the valve-casing, and that when one of said pair of port openings in the valve-member registers partially with its coöperating port opening in the valve-casing the other one of said pair will simultaneously register proportionally with its coöperative port opening in the valve-casing, and said pair of port openings in the second-mentioned valve-member being so arranged with respect to the port opening in the first mentioned chambered valve-member, that the registration of said pair of port openings with their coöperating port openings in the valve-casing occurs when the port opening in the first-mentioned valve-member registers with the port opening in the valve-casing which communicates with one of said discharge nozzles, a second pair of port openings in the second mentioned chambered valve-member corresponding to said first mentioned pair of port openings therein and being so arranged with respect thereto and to the port opening in the first mentioned chambered valve-member, that

they register with the port openings in the valve-casing which communicate with the supply pipes when the port opening in the first-mentioned chambered valve-member communicates with the port opening in the valve-casing communicating with the other discharge nozzle, and means for simultaneously manipulating said chambered valve-members and also for manipulating the valve which controls the passage-way between the two chambers in the valve-casing.

5. A two-way faucet comprising a valve-casing having two chambers therein which are connected by a passage-way, a valve for controlling said passageway, a discharge nozzle leading from said valve-casing and communicating with one of said chambers through a port opening therein, and a second discharge nozzle leading from said valve-casing and communicating with said chamber through a second port opening, a chambered valve-member in said mentioned chamber in the valve-casing, said valve-member having a port arranged to alternately register with said port openings which communicate with the discharge nozzles, two supply pipes communicating with the second chamber in said valve-casing through separate port openings therein, a chambered valve-member in said second mentioned chamber in the valve-casing, said second mentioned valve-member having a pair of port openings which are arranged to register with the port openings in the valve-casing which communicate with the supply pipes, said pair of port openings in the valve-member being arranged so that when one of them registers fully with its coöperating port opening in the valve-casing the other one of said pair of port openings will not register with its coöperating port opening in the valve-casing and said pair of port openings being also arranged so that when one of them registers partially with its coöperating port opening in the valve-casing the other one of said pair will simultaneously register proportionately with its coöperating port opening in the valve-casing, and said pair of port openings in the second mentioned valve-member being so arranged with respect to the port opening in the first mentioned valve-member that the registration of said pair of ports with the port openings in the valve-casing communicating with the supply pipes occurs when the port opening in the first mentioned valve-member registers with the port opening in the valve-casing communicating with one of said discharge nozzles, a second pair of port openings in the second mentioned valve-member corresponding to the first mentioned pair of port openings therein and being so arranged with respect thereto and to the port opening in the first mentioned valve-member that registration with the port

openings in the valve-casing which communicate with the supply pipes occurs when the port opening in the first mentioned valve-member registers with the port opening 5 which communicates with the second discharge nozzle, and a device for simultaneously operating said chambered valve-members and also for operating the valve which controls the passageway between the two 10 chambers in the valve-casing, said device being arranged and adapted for separate actuation for its two functions.

6. A two-way faucet comprising a valve-casing which is provided with two cylindrically bored chambers which are arranged in axial alignment and connected by an axially arranged passageway, a cylindrical, chambered valve-member rotatably fitted in each of said chambers in the valve-casing, 15 said valve-members being closed at their outer ends, the end walls of said valve-members being provided with axial openings, a rod fitted through said openings in the end walls of said valve-members and adapted to 20 be reciprocated longitudinally therethrough, but being fixed to rotate with said valve-members, a valve on said rod arranged to close the passageway between the two chambers in the valve-casing, heads secured to 25 the opposite ends of the valve-casing and adapted to retain the valve-members in place, two discharge nozzles leading from said valve-casing and communicating with 30 one of the cylindrical chambers therein 35 through separate port openings, the valve-member in said chamber being provided with a port opening which is adapted to alternately open communication through the port openings which communicate with 40 the discharge nozzles, two supply pipes leading to the valve-casing and communicating with the second cylindrical chamber through separate port openings, the valve-member in said second mentioned chamber 45 being provided with a pair of port openings which are adapted to establish communication through the port openings in the valve-casing which communicate with said supply pipes, said pair of port openings in 50 the valve-member being so arranged that when one of them registers fully with its co-operating port opening in the valve-casing the other one of said pair will not register with its co-operating port opening in the 55 valve-casing, and said pair of port openings being also arranged to simultaneously register proportionately with both of said port openings in the valve-casing, said valve-member also having a second pair of 60 port openings which are arranged similarly to said first mentioned pair of openings, said two pair of openings being so arranged with respect to the port opening in the valve-member in the first mentioned chamber that 65 when said port opening communicates with

either of the port openings in the valve-casing which communicates with the discharge nozzles, communication is established through the port openings communicating with the supply pipes, and a handle arranged to rotate the rod to simultaneously manipulate the valve-members in the two chambers in the valve-casing and being also adapted to reciprocate said rod to manipulate the valve which controls the passageway 75 between said chambers.

7. A two-way faucet comprising a valve-casing which is provided with two cylindrically bored chambers which are arranged in axial alignment and connected by an axial 80 passageway, two discharge nozzles leading from said valve-casing and communicating with one of said chambers through separate port openings, two supply pipes leading to 85 said valve-casing and communicating with the second chamber through separate port openings, each of said port openings being of substantially the same area, a cylindrical, chambered valve-member rotatably mounted in said second chamber and having a pair 90 of port openings one of which is adapted to register with one of the port openings in the valve-casing which communicate with said supply pipes, each of said pair of port 95 openings being of substantially the same area as its co-operating port in the valve-casing, and being so arranged that when communication is fully established through one of said port openings which communicates with one of the supply pipes, communication is cut off from the port opening which communicates with the other supply pipe, said pair of port openings in the valve-member being also arranged to simultaneously establish proportionate communication 100 through both of said port openings which communicate with said supply pipes, said valve-member also having a second pair of similarly arranged port openings, a cylindrical, chambered valve-member in the 105 first-mentioned chamber in the valve-casing, said valve-member having a port opening which is adapted to alternately establish communication through the port openings in the valve-casing which communicate with 110 the discharge nozzles, the port opening in said valve-member being located with respect to the two pair of port openings in the valve-member in the second chamber and of sufficient area to establish full communication 115 through either of its co-operating port openings in the valve-casing which communicates with the discharge nozzle, when communication is established through the respective port openings which communicate with the supply pipes, or when communication is simultaneously established proportionately through said port openings, and a device for simultaneously manipulating 120 the two cylindrical valve-members and 125 130

- also for manipulating the valve which controls the passageway between the two chambers, said device comprising a rod which is arranged to rotate said cylindrical valve-members and independently reciprocate the valve which controls the passageway, and a handle arranged to impart both a reciprocating and rotatory motion to said rod.
8. A two-way faucet comprising a valve-casing provided with two independent chambers, two discharge nozzles leading from the casing, means for conducting into one of said chambers fluids from two independent sources of supply, a rotatory valve-member for alternately establishing communication between the other chamber and either of the discharge nozzles, and means for effecting a discharge of the fluid from the first-mentioned chamber into the second-mentioned 20 chamber and to the particular discharge nozzle at the time in communication with said second-mentioned chamber.
9. A two-way faucet comprising a valve-casing provided with two independent chambers, two discharge nozzles leading from the casing, means for conducting into one of said chambers fluids from independent sources of supply, a rotatory valve-member for alternately establishing communication 25 between the other chamber and either of the discharge nozzles, a rotatory valve-member for proportioning the quantity of the respective fluids admitted into the first-mentioned chamber, and a reciprocatory valve disposed in the line of the common axis of rotation of the rotatory valve-members for admitting the fluid from the first-mentioned chamber into the second-mentioned chamber and to the particular discharge nozzle in 30 communication with said second-mentioned chamber.
10. A two-way faucet comprising a valve-casing provided with two independent chambers, two discharge nozzles leading from the casing, means for conducting into one of said chambers fluids from independent sources of supply, means for controlling the proportions of the respective fluids admitted into said chamber, a rotatory valve-member for alternately establishing communication 35 between the other chamber and either of the discharge nozzles, and a valve for admitting the fluid from the first-mentioned chamber into the second-mentioned chamber and to the particular nozzle in communication with said second-mentioned chamber.
11. A two-way faucet comprising a valve-casing provided with two independent contiguous chambers separated by a partition, two discharge nozzles leading from the casing, means for conducting into one of the chambers liquids from independent sources of supply, a rotatory valve-member in said chamber for controlling the proportions of 40
- the respective liquids admitted thereto, a rotatory valve-member in the other chamber for alternately establishing communication between said chamber and either of the discharge nozzles, a reciprocatory valve in one of the chambers for controlling communication between the two chambers, a rotatory and reciprocating actuating member coupled to said reciprocatory valve and disposed about the common axis of the rotatory valve-members and movably coupled to the latter, whereby said rotatory valve-members may be simultaneously rotated and the reciprocating valve may be reciprocated independently thereof, and a single manipulating device for imparting rotatory and reciprocating motion to said actuating member.
12. In a faucet, a valve-casing provided with two separate chambers, means for conducting into one of said chambers fluids from independent sources of supply, two discharge nozzles leading from the other chamber, means for establishing communication between said members, and means for controlling the proportions of the respective fluids admitted into said first-mentioned chamber and for simultaneously establishing communication through either of the discharge nozzles.
13. A two-way faucet comprising a valve-casing provided with two chambers, two discharge nozzles leading from one of said chambers, means for alternately establishing communication between said chamber and either of the discharge nozzles, means for conducting into the other chamber fluids from two independent sources of supply, means for controlling the proportions of the respective fluids admitted into said second-mentioned chamber, means for establishing communication between said chambers, and a single manipulating device common to all of the controlling devices.
14. A faucet comprising a casing chambered for the initial influx of liquids from independent sources of supply, a secondary chamber in said casing, two discharge nozzles leading from said secondary chamber, a rotatable member for controlling the relative proportions of the liquids admitted into said first-mentioned chamber and for establishing communication through either of the discharge nozzles, and a reciprocating member cooperatively connected to the rotatable member for controlling the passage of the liquid from one chamber into the other.
